UNITED STATES PATENT OFFICE

135,359

DESIGN FOR A CARRYING CASE OR SIMILAR ARTICLE

Benjamin Boyar, Woodmere, N. Y.

Application February 11, 1943, Serial No. 109,524

Term of patent 7 years

To all whom it may concern:

Be it known that I, Benjamin Boyar, a citizen of the United States and a resident of Woodmere, Nassau County, State of New York, have invented a new, original, and ornamental Design for a Carrying Case or Similar Article, of which the following is a specification, reference being had to the accompanying drawings, forming a part thereof, in which:

Fig. 2 is a rear elevational view thereof;
Fig. 3 is a plan view of the case shown in Figs. 1 and 2, in open position.

Fig. 4 is a section on the line 4—4 of Fig. 3; and
Fig. 5 is a section on the line 5—5 of Fig. 3.

I claim:

The ornamental design for a carrying case or similar article, as shown.

BENJAMIN BOYAR.
